VICTOR H. VOLAND, OF CLAYTON, MISSOURI, ASSIGNOR TO VOLAND SCENIC STUDIOS, INC., OF ST. LOUIS, MISSOURI, A CORPORATION OF MISSOURI

OPERATING MEANS FOR CURTAIN DROPS

Application filed August 23, 1926. Serial No. 131,092.

My invention relates to improvements in means for operating curtain drops, in which each curtain drop together with the hoisting mechanism and other accessories are combined into a single unit. The object of this invention is to effect such a combination providing a curtain drop of greater ease of operation and installation.

I accomplish these results by the device herein described and illustrated.

Fig. I is a front elevation of a curtain drop constructed in accordance with my invention.

Fig. II is a fragmentary front elevation of the hoist mechanism, showing the lock and signal light arrangement.

Fig. III is a side elevation of the same.

Fig. IV is a plan view of the same.

1 designates a variable counterweight movably engaging a vertical track 2. Ropes 3 are secured to said counterweight at one end, and at the other end to a curtain 4, said ropes first passing up over a battery of sheaves 5 and down over sheaves 6. A rope 7 secured to the upper and lower part of the counterweight 1, as shown, passes over a sheave in the battery of sheaves 5 and around a sheave 8, said sheave being carried in a movable bipartite weight 9, said weight keeping the rope 7 at all times taut. 10 designates rods preferably four in number, on which the bipartite weight 9 moves.

Secured to a flat top member 11 (Fig. II) is a locking mechanism 12. Fingers 13, pivotally secured, as shown, within the frame 14, shown in section, rigidly clamp the rope 7 when in a locked position. A screw bolt 15, screwed through an aperture in the frame 14, bears against the fingers 13 from one side, while a cam lever 16, secured to the opposite side of the frame, bears against said fingers 13 from the other side, to effect said clamping. 17 designates a metal loop girdling the rope 7 and the lever 16, to hold said lever in a locked position when desired.

Mounted in the guard box 18 is an incandescent lamp 19 provided with a switch 20, said guard box being secured to a forwardly projecting end of the top member 11.

At a particular time during a theatrical performance the lamp 19 may be caused to light, indicating to an attendant that a certain curtain is wanted, and by opening the lock 12 and pulling the rope 7, the curtain is raised or lowered as desired. Prior to this invention such devices were without individual locking devices and signal lamps. A makeshift rack carrying a plurality of locking devices extended along the battery of curtain drops, which necessitated costlier installation and less satisfactory service. At such time also the overhead lights used at the side of the stage considerably interfered with stage lighting effects. It is readily apparent how individual lights remove this difficulty, and also provide a ready means of insuring prompt and reliable action.

I claim:

1. An improved appliance for operating curtain drops comprising, in combination, a vertically movable counter-balance weight, connections extending between the weight and a curtain drop adapted to be operated thereby, an anchor rope extending from the counter-balance weight, means including a pair of pivoted fingers between which the anchor rope passes for rigidly securing the anchor rope, and means interposed between the securing means and the counter-balance weight for maintaining the anchor rope in a taut condition.

2. An improved appliance for operating curtain drops comprising, in combination, a vertically movable counter-balance weight, connections extending between the weight and a curtain drop adapted to be operated thereby, an anchor rope having one of its extremities secured to the upper portion of the counter-balance weight and its opposite extremity secured to the lower portion of

the counter-balance weight, means for rigidly securing the anchor rope, said means including a pair of pivoted fingers between which the anchor rope passes, and means for controlling movement of said fingers, and a weight associated with the anchor rope and adapted to maintain the rope in a taut condition.

In testimony that I claim the foregoing
I hereunto affix my signature.

VICTOR H. VOLAND.
